(57) **CLAIM**

The ornamental design for a finger exerciser, as shown and described.

DESCRIPTION

FIG. 1 is a perspective view of a finger exerciser design showing my new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is an enlarged view of a portion indicated with “8” in FIG. 7; and,

FIG. 9 is an enlarged view of a portion indicated with “9” in FIG. 7.

The broken lines in FIGS. 7-9 are for the purpose of depicting the boundary lines of the enlarged views and form no part of the claimed design.

1 Claim, 9 Drawing Sheets
